UNITED STATES PATENT OFFICE

CARL PALMER PARK, OF MANCHESTER, NEW HAMPSHIRE, ASSIGNOR TO U. S. BOBBIN & SHUTTLE COMPANY 1929, OF PROVIDENCE, RHODE ISLAND, A CORPORATION OF RHODE ISLAND

MULTIPLE BIT BORING MACHINE

Application filed January 22, 1931. Serial No. 510,494.

This machine is for the purpose of boring at the same time a number of series of radial holes in an article, more particularly in the barrel of a spool.

5 In the barrels of such spools, there is a central hole extending along the axis and around it a plurality of other parallel holes and it is desirable to bore into these last named holes a series of radial passages.

10 As shown, this machine is intended to bore three longitudinal sets of radial holes each set comprising four, the total being twelve holes all radially disposed.

15 In the drawings, Fig. 1 is a plan view of the device showing the bits withdrawn.

Fig. 2 is a plan view showing the bits advanced.

Fig. 3 is a perspective of the machine viewed from the front.

20 Fig. 4 is a vertical sectional detail of a spool in position with the bits retracted.

Fig. 5 is an enlarged horizontal section looking down on the line 5—5 of Fig. 4.

25 Fig. 6 is a vertical section of Fig. 5 on the line 6—6 looking in the direction of the arrow, the spool being removed.

In the drawings, A represents a frame which is shown as supported by a column 10.

30 9 is a table or base at a convenient height for the operator and, as shown, there are three sets of supporting rods 11, 12 and another set not shown which carry adjustably the brackets 14, 15 and 16 which support respectively the three motors M¹, M² and M³ and also the ways K¹, K² and K³ for the multiple bit driving heads H¹, H² and H³.

35 By means of suitable tightening bolts such as indicated at 17 the brackets with the motors and heads can be adjusted by moving back and forth towards the center of the machine.

As shown, the motors are driven by suitable electrical conductors carried by suitable housings X, Y and Z.

40 R is a work rest which supports the work shown as a spool W having a central hole 1 and other holes 2, 3 and 4.

Rest R includes a base 20 from which projects upwardly at the center of the rest the work holding center pin 21 and a positioning

pin 22 which must be shorter than the center pin and is in position to enter anyone of the holes 2, 3 or 4 in the work.

The spool, as shown, has a barrel 5 through which are the longitudinal holes 1, 2, 3 and 4 into which enter the radial holes bored by the three sets of vertically alined bits such as 41, 42, 43 and 44. Longitudinal holes 1, 2, 3, 4 also usually extend through the heads 6 and 7. 55

I find it convenient to use the bit guides G¹, G² and G³ fixed to frame A and spaced around center pin 20, each guide being provided with a vertical series of radially disposed bit guide holes 31, 32, 33, 34. 60 65

These holes in each guide are in vertical alinement and preferably taper from a large size outside to a smaller size inside, their purpose being to steady the drills 41, 42, 43, 44, as the driving heads move inward. 70

The bit guides G¹, G² and G³ are spaced around the center pin and are shown as at equal distances.

The positioning pin 22 should be in line with one of the series of holes in one of these bit guides. 75

K¹, K² and K³ indicate sets of head guideways radially disposed around the center pin 21. As shown, each comprises two rods upon which slides a yoke 40 forming part of one of the heads H¹, H² and H³. 80

Extending down from each yoke is a head link pivot such as 61.

Each head such as H¹ includes a barrel 45 attached to a yoke 40 and slidably in and out of a casing 46. 85

This construction of head is well known and it is not deemed necessary to describe the interior mechanism by which each motor drives a set of vertically alined revoluble bits 41, 42, 43, 44. 90

These bits are horizontally alined with the holes 31, 32, 33, 34 in each bit guide, if bit guides are used.

Each head is slidable on a set of ways to and from the center pin and each has pivoted to its head link pivot, a link such as L¹, L² or L³ the other end of which link is pivoted to a handle link pivot such as 51, 52 or 53. 95

These last named pivots are carried by a 100

handle T pivoted at 50 so that its center of movement is directly in line with the center of center pin 21 said pivots being spaced around said pin.

5 L^1 , L^2 and L^3 are operating links each pivoted at one end to a handle link pivot 51, 52, or 53 and at the other end to a head link pivot such as 61.

10 The center pin 21 should fit the center hole 1 snugly and should extend up far enough so that it will hold the top of spool W steady while the short positioning pin 22 should extend up to the position below the lowest bit. Pin 21 should terminate in a point 121 and pin 22 in a point 122 so that a spool can more 15 readily be put in place.

15 I prefer also to use a skeleton spool head guide S which as shown carries also the bit guides G^1 , G^2 and G^3 and has holes corresponding with those in the bit guides.

20 Preferably the whole assembly can be attached or detached as by the use of cap screws 55 shown in Fig. 6 and preferably head guide S is formed as a ring at the bottom 50 and with a plurality of openings 151, 151 through which a spool can be reached while the top is chamfered and 52 whereby a spool can readily be slipped in place on the pins and can afterwards be quickly removed by reaching in through the openings 51.

30 As shown in Fig. 6, the spool heads may fit snugly inside of guide S or loosely as shown in Fig. 4 as the center pin 21 and positioning pin 22, if they fit their respective holes such as 1 and 3, will hold the spool accurately in place while it is being bored.

35 In fact both the bit guides G^1 , G^2 , G^3 and the head guide S can be entirely removed or omitted if desired.

40 I claim:

1. The combination in a multiple bit boring machine; of a frame; a work rest carried by the frame and having an upwardly projecting work holding centre pin and a positioning pin; a plurality of vertical bit guides spaced around the centre pin each having a vertical series of radial bit guide holes; a plurality of sets of head guide ways radially disposed around the centre pin; a plurality 45 of multiple bit driving heads each head having a set of vertically aligned revoluble bits each set being in horizontal alinement with a series of bit guide holes, each head being slideable on a set of ways towards and from the centre pin and each head having a link pivot; an operating handle pivoted on the frame on the same centre with the centre pin and having handle link pivots spaced around said centre; and a plurality of operating links, each pivoted at one end to a handle link pivot and at the other end to a head link pivot.

50 2. The combination in a multiple bit boring machine; of a frame; a work rest carried by the frame and having an upwardly projecting work holding centre pin and a posi-

tioning pin; a plurality of sets of head guide ways radially disposed around the centre pin; a plurality of multiple bit driving heads each head having a set of vertically aligned revoluble bits, each head being slideable on a set of ways towards and from the centre pin and each head having a link pivot; an operating handle pivoted on the frame on the same centre with the centre pin and having handle link pivots spaced around said centre; and a plurality of operating links, each pivoted at one end to a handle link pivot and at the other end to a head link pivot.

55 3. The combination in a multiple bit boring machine; of a frame; a work rest carried by the frame; a plurality of sets of head guide ways radially disposed around the work rest; a plurality of multiple bit driving heads each head having a set of vertically aligned revoluble bits, each head being slideable on a set of ways towards and from the work rest and each head having a link pivot; an operating handle pivoted on the frame on the same centre with the work rest and having handle link pivots spaced around said centre; and a plurality of operating links, each pivoted at one end to a handle link pivot and at the other end to a head link pivot.

60 4. The combination in a multiple bit boring machine, of a frame; a work rest carried by the frame and having an upwardly projecting work holding centre pin and a positioning pin; a plurality of sets of head guide ways radially disposed around the centre pin; a plurality of multiple bit driving heads each head having a set of vertically aligned revoluble bits, each head being slideable on a set of ways towards and from the centre pin; and means to move the heads to and from the centre pin.

65 5. The combination in a multiple bit boring machine, of a frame; a work rest carried by the frame and having an upwardly projecting work holding centre pin and a positioning pin; a plurality of sets of head guide ways radially disposed around the centre pin; a plurality of bit driving heads each head having a revoluble bit, each head being slideable on a set of ways towards and from the centre pin; and means to move the heads to and from the centre pin.

CARL PALMER PARK.
